HOLDER FOR TOOTHBRUSHES AND TUMBLER

Dwight E. Woolever, 3671 S. Broadway,
Los Angeles, Calif.

Filed Dec. 14, 1964, Ser. No. 83,026

Term of patent 14 years

(Cl. D4—3)

FIG. 1 is a fragmentary front elevational view of a holder for toothbrushes and tumbler, in closed position, showing my new design;

FIG. 2 is a fragmentary front elevational view thereof, in open position;

FIG. 3 is a top plan view thereof, in closed position;

FIG. 4 is a top plan view thereof, in open position; and

FIG. 5 is an enlarged cross-sectional view thereof taken on the line 5—5 of FIG. 2.

A portion of the article is broken away in FIG. 5 to indicate indeterminate length.

I claim:

The ornamental design for a holder for toothbrushes and tumbler, substantially as shown and described.
